US0D1031695S

(12) **United States Design Patent** (10) Patent No.: **US D1,031,695 S**
(45) Date of Patent: ** Jun. 18, 2024

(54) **IN-CAR SPEAKER**

(71) Applicant: **ALPS ALPINE CO., LTD.**, Tokyo (JP)

(72) Inventor: **Masatada Muramoto**, Ota-ku (JP)

(73) Assignee: **ALPS ALPINE CO., LTD.**, Tokyo (JP)

(**) Term: **15 Years**

(21) Appl. No.: **29/816,969**

(22) Filed: **Nov. 26, 2021**

(30) **Foreign Application Priority Data**

May 26, 2021 (JP) ..... 2021-011193 D

(51) **LOC (14) Cl.** **14-01**

(52) **U.S. Cl.**

USPC **D14/216**
